UNITED STATES PATENT OFFICE.

LOUIS F. CLAUSING, OF BURLINGAME, CALIFORNIA.

HEATER.

1,418,361.

Specification of Letters Patent. Patented June 6, 1922.

Application filed December 5, 1921. Serial No. 520,035.

To all whom it may concern:

Be it known that I, LOUIS F. CLAUSING, a citizen of the United States, and resident of Burlingame, county of San Mateo, and 5 State of California, have invented a new and useful Heater, of which the following is a specification.

The present invention relates to improvements in gas heaters and the principal object of the invention is to provide a gas heater that has a maximum amount of radiating surface in as little space as possible. 10 A further object of the invention is to provide a heater of the character described in 15 which the burned gas comes in no wise in contact with the air of the room to be heated, but is only used to heat a large radiating surface, whereupon it is guided into a smoke-stack. A further object of the invention 20 is to provide heat radiating means particularly adapted to receive heat units from the burning gas over a large area and to allow the air to be heated to pass over its outer surface, thereby transmitting the heat units received 25 immediately to the air to be heated.

With these objects in view, I have illustrated the preferred form of my invention in the accompanying drawing, in which Figure 1 represents a vertical cross section through 30 my heater; Figure 2 a top plan view of the same and Figure 3 a horizontal section through the same along line 3-3 of Figure 1.

While the drawings show only the preferred form of the invention, I wish to have it understood that various changes or modifications may be made within the scope of the claims hereto attached without departing from the spirit of the invention.

40 My heater comprises a preferably rectangular housing (1) provided with outwardly extending flanges (2) at its top. My device is designed to extend downwardly from the floor of the room to be heated and it is 45 supported on the floor by means of the flanges (2). The flanges are preferably arranged relative to the floor in such a manner that the perforated cover (3) for the housing is substantially flush with the floor. 50 The bottom of the housing is flanged inwardly as shown at (4) and supports the bottom plate (6) which is provided with a large central hole (7) adapted to receive the radiator (8) which is secured to the

flange (9) extending downwardly from the 55 bottom plates by means of suitable bolts (11).

It will be seen from the drawings that the principal portion of the radiator is enclosed by the housing, while a somewhat reduced portion extends below the same. The 60 particular shape of the radiator is the most essential part of my invention. It is preferably made of corrugated sheet metal. The corrugations, however, are of considerably larger dimensions than is usually the case. 65 A strip of this corrugated metal is turned into preferably tubular form so that the corrugations are disposed vertically. It will be readily understood that in this manner a tubular central space (16) is provided with 70 which communicate a rather large number of channels formed by the corrugations. These channels (17) adjoining the central space will be hereafter referred to as the inner channels as contradistinguished from 75 the outer channels of the radiator which communicate directly with the space between the radiator and the housing. The radiator is closed on top, which is effected by covering the central space with a suitable cap 80 (18) and by closing the inner channels which is preferably done by welding the upper edges defining the inner channels together. In a similar manner the outer channels (19) are closed at the bottom so that 85 there is no communication whatever between the inside of the radiator and the housing while the inner channels connect directly with the lower portion of the radiator and the outer channels directly with the upper 90 portion of the housing.

The burner (21) fed by the pipe (22) may be of any desired construction and is enclosed by a pipe (23) extending into the radiator through a desired distance sufficient 95 to guide the products of combustion into the interior of the radiator and to avoid any interference of ventilation currents with the direct rising of the said products. The pipe (23) is supported by means of a second 100 pipe (24) extending sideways from the same which latter is secured to the wall of the radiator by means of bolts (26). Preferably opposite the latter pipe (24) is provided an outlet (27) leading preferably into the 105 chimney. The structure is open at the bottom and prevents too much draft from passing over the burner.

The top plate (3) has a downwardly extending flange (31) to which is secured a large tube (32) which extends downwardly so as to cover a considerable portion of the 5 radiator as shown in Figure 1.

The operation of my gas heater will be easily understood. The products of combustion are carried upward inside the pipe (23), its open bottom providing ample 10 ventilation, and rises in the central portion of the radiator until it arrives near the top of the latter. A draft is created through the pipe (27) during this process, whereby air will be drawn from the space surrounding 15 the pipe (23) into the chimney. Since this draft affects only the outer portion of the lower part of the radiator, the inner portion being protected by the pipe (23), a partial 20 vacuum is created in the inner channels, whereby the products of combustion which have risen to the top in the central portion 25 of the radiator is caused to turn around and to pass downwardly through the inner channels until it reaches the pipe (27) and is drawn into the chimney. During this time most of the heat units carried by the products of combustion have been absorbed by the radiator which communicates the same to the air contained in the outer channels. 30 This air upon being heated begins to rise. Being separated from the housing by means of the large tube (32) it does not affect to any considerable extent the air enclosed between the tube (32) and the housing. 35 While this air rises through the perforated top plate it naturally creates a partial vacuum in the lower portions of the outer channels and this vacuum will be filled from the air outside the tube (32) so that a natural 40 circulation is created, the hot air rising in the outer channels and the cool air coming

downward through the space enclosed between the tube (32) and the housing. It will be seen that in this manner a large radiating surface is provided and that the 45 heat contained in the products of combustion is rapidly transmitted to the outer channels through the medium of the corrugated radiating surface from where it rises into the room to be heated while cool air is simultaneously withdrawn from the same room and fed into the outer channels.

My device is not confined to the form illustrated in the drawings. It will be understood that the same may be placed on 50 the floor of the basement like a furnace, in which case communication between the room to be heated and the heater is established by the use of proper pipes. The register or 55 perforated cover (3) may also be disposed 60 in the wall of the rooms to be heated, in which case the heater is placed underneath the wall and connected directly to the register box.

I claim:

1. In a heater of the character described, a radiator comprising a strip of corrugated sheet metal bent into tubular form so as to present inner and outer channels, the walls defining the outer channels being joined at 70 one end and the walls defining the inner channels being joined at the other end.

2. In a heater of the character described, a one-piece radiator comprising a strip of corrugated sheet metal bent into tubular 75 form so as to present inner and outer channels, the walls defining the outer channels being brought together and joined at one end and the walls defining the inner channels being brought together and joined at 80 the other end.

LOUIS F. CLAUSING.
